[57] CLAIM

The ornamental design for a clamp, as shown and described.

DESCRIPTION

FIG. 1 is an open-end elevation view of the clamp;
FIG. 2 is a side elevation view of the clamp; it is understood that the other side elevation view is the same;
FIG. 3 is a closed-end elevation view of the clamp;
FIG. 4 is a top-plan view of the clamp; and,
FIG. 5 is a bottom-plan view of the clamp.

FIG. 1

FIG. 2

FIG. 3

FIG. 4

FIG. 5
